COMBINED SWING FAUCET AND DISHWASHING FIXTURE

Herbert Carvel Moore, West Los Angeles, Calif., assignor
to Electro-Way Corporation, Los Angeles, Calif., a corporation

Application March 19, 1956, Serial No. 40,672

Term of patent 14 years

(Cl. D91—3)

Fig. 2.

Fig. 3.

Figure 1 is a perspective view of a combined swing faucet and dishwashing fixture showing my new design;

Figure 2 is a top plan view; and

Figure 3 is a side view.

The dominant features of my new design are shown in full lines.

I claim:

The ornamental design for a combined swing faucet

and dishwashing fixture, substantially as shown and described.
